(57) **ABSTRACT**

A fluid ejection chip includes a substrate. A plurality of nozzle arrangements is positioned on the substrate. Each nozzle arrangement includes a nozzle chamber defining structure which defines a nozzle chamber and which includes a wall in which a fluid ejection port is defined. Each nozzle arrangement includes at least one actuator for ejecting fluid from the nozzle chamber through the fluid ejection port. The, or each, actuator is displaceable with respect to the substrate on receipt of an electrical signal. The, or each, actuator is formed in said wall of the nozzle chamber defining structure, so that displacement of the, or each, actuator results in a change in volume of the nozzle chamber so that fluid is ejected from the fluid ejection port.

STATEMENT REGARDING FEDERALLY SPONSORED RESEARCH OR DEVELOPMENT

Not applicable.

FIELD OF THE INVENTION

The present invention relates to the field of fluid ejection and, in particular, discloses a fluid ejection chip.

BACKGROUND OF THE INVENTION

Many different types of printing mechanisms have been invented, a large number of which are presently in use. The known forms of printers have a variety of methods for marking the print media with a relevant marking media. Commonly used forms of printing include offset printing, laser printing and copying devices, dot matrix type impact printers, thermal paper printers, film recorders, thermal wax printers, dye sublimation printers and ink jet printers both of the drop on demand and continuous flow type. Each type of printer has its own advantages and problems when considering cost, speed, quality, reliability, simplicity of construction and operation etc.

In recent years the field of ink jet printing, wherein each individual pixel of ink is derived from one or more ink

nozzles, has become increasingly popular primarily due to its inexpensive and versatile nature.

Many different techniques of ink jet printing have been invented. For a survey of the field, reference is made to an article by J Moore, "Non-Impact Printing: Introduction and Historical Perspective", Output Hard Copy Devices, Editors R Dubeck and S Sherr, pages 207-220 (1988).

Ink Jet printers themselves come in many different forms. The utilization of a continuous stream of ink in ink jet printing appears to date back to at least 1929 wherein U.S. Pat. No. 1,941,001 by Hansell discloses a simple form of continuous stream electro-static ink jet printing.

U.S. Pat. No. 3,596,275 by Sweet also discloses a process of a continuous ink jet printing including a step wherein the ink jet stream is modulated by a high frequency electro-static field so as to cause drop separation. This technique is still utilized by several manufacturers including Elmjet and Scitex (see also U.S. Pat. No. 3,373,437 by Sweet et al).

Piezoelectric ink jet printers are also one form of commonly utilized ink jet printing device. Piezoelectric systems are disclosed by Kyser et. al. in U.S. Pat. No. 3,946,398 (1970) which utilizes a diaphragm mode of operation, by Zolten in U.S. Pat. No. 3,683,212 (1970) which discloses a squeeze mode form of operation of a piezoelectric crystal, Stemme in U.S. Pat. No. 3,747,120 (1972) which discloses a bend mode of piezoelectric operation, Howkins in U.S. Pat. No. 4,459,601 which discloses a piezoelectric push mode actuation of the ink jet stream and Fischbeck in U.S. Pat. No. 4,584,590 which discloses a shear mode type of piezoelectric transducer element.

Recently, thermal ink jet printing has become an extremely popular form of ink jet printing. The ink jet printing techniques include those disclosed by Endo et al in GB 2007162 (1979) and Vaught et al in U.S. Pat. No. 4,490,728. Both the aforementioned references disclose ink jet printing techniques which rely on the activation of an electrothermal actuator which results in the creation of a bubble in a constricted space, such as a nozzle, which thereby causes the ejection of ink from an aperture connected to the confined space onto a relevant print media. Manufacturers such as Canon and Hewlett Packard manufacture printing devices utilizing the electro-thermal actuator.

As can be seen from the foregoing, many different types of printing technologies are available. Ideally, a printing technology should have a number of desirable attributes. These include inexpensive construction and operation, high-speed operation, safe and continuous long-term operation etc. Each technology may have its own advantages and disadvantages in the areas of cost, speed, quality, reliability, power usage, simplicity of construction and operation, durability and consumables.

Applicant has developed a substantial amount of technology in the field of micro-electromechanical inkjet printing. The parent application is indeed directed to a particular aspect in this field. In this application, the Applicant has applied the technology to the more general field of fluid ejection.

SUMMARY OF THE INVENTION

In accordance with a first aspect of the present invention, there is provided a nozzle arrangement for an ink jet printhead, the arrangement comprising a nozzle chamber defined in a wafer substrate for the storage of ink to be ejected; an ink ejection port having a rim formed on one wall of the chamber; and a series of actuators attached to the

wafer substrate, and forming a portion of the wall of the nozzle chamber adjacent the rim, the actuator paddles further being actuated in unison so as to eject ink from the nozzle chamber via the ink ejection nozzle.

The actuators can include a surface which bends inwards away from the center of the nozzle chamber upon actuation. The actuators are preferably actuated by means of a thermal actuator device. The thermal actuator device may comprise a conductive resistive heating element encased within a material having a high coefficient of thermal expansion. The element can be serpentine to allow for substantially unhindered expansion of the material. The actuators are preferably arranged radially around the nozzle rim.

The actuators can form a membrane between the nozzle chamber and an external atmosphere of the arrangement and the actuators bend away from the external atmosphere to cause an increase in pressure within the nozzle chamber thereby initiating a consequential ejection of ink from the nozzle chamber. The actuators can bend away from a central axis of the nozzle chamber.

The nozzle arrangement can be formed on the wafer substrate utilizing micro-electromechanical techniques and further can comprise an ink supply channel in communication with the nozzle chamber. The ink supply channel may be etched through the wafer. The nozzle arrangement may include a series of struts which support the nozzle rim.

The arrangement can be formed adjacent to neighbouring arrangements so as to form a pagewidth printhead.

In this application, the invention extends to a fluid ejection chip that comprises

a substrate; and

a plurality of nozzle arrangements positioned on the substrate, each nozzle arrangement comprising

a nozzle chamber defining structure which defines a nozzle chamber and which includes a wall in which a fluid ejection port is defined; and

at least one actuator for ejecting fluid from the nozzle chamber through the fluid ejection port, the, or each, actuator being displaceable with respect to the substrate on receipt of an electrical signal, wherein

the, or each, actuator is formed in said wall of the nozzle chamber defining structure, so that displacement of the, or each, actuator results in a change in volume of the nozzle chamber so that fluid is ejected from the fluid ejection port.

Each nozzle arrangement may include a plurality of actuators, each actuator including an actuating portion and a paddle positioned on the actuating portion, the actuating portion being anchored to the substrate and being displaceable on receipt of an electrical signal to displace the paddle, in turn, the paddles and the wall being substantially coplanar and the actuating portions being configured so that, upon receipt of said electrical signal, the actuating portions displace the paddles into the nozzle chamber to reduce a volume of the nozzle chamber, thereby ejecting fluid from the fluid ejection port.

A periphery of each paddle may be shaped to define a fluidic seal when the nozzle chamber is filled with fluid.

BRIEF DESCRIPTION OF THE DRAWINGS

Notwithstanding any other forms which may fall within the scope of the present invention, preferred forms of the invention will now be described, by way of example only, with reference to the accompanying drawings in which:

FIGS. 1-3 are schematic sectional views illustrating the operational principles of the preferred embodiment;

FIG. 4(a) and FIG. 4(b) are again schematic sections illustrating the operational principles of the thermal actuator device;

FIG. 5 is a side perspective view, partly in section, of a single nozzle arrangement constructed in accordance with the preferred embodiments;

FIGS. 6-13 are side perspective views, partly in section, illustrating the manufacturing steps of the preferred embodiments;

FIG. 14 illustrates an array of ink jet nozzles formed in accordance with the manufacturing procedures of the preferred embodiment;

FIG. 15 provides a legend of the materials indicated in FIGS. 16 to 23; and

FIG. 16 to FIG. 23 illustrate sectional views of the manufacturing steps in one form of construction of a nozzle arrangement in accordance with the invention.

DESCRIPTION OF PREFERRED AND OTHER EMBODIMENTS

20

In the following description, reference is made to the ejection of ink for application to ink jet printing. However, it will readily be appreciated that the present application can be applied to any situation where fluid ejection is required.

In the preferred embodiment, ink is ejected out of a nozzle chamber via an ink ejection port using a series of radially positioned thermal actuator devices that are arranged about the ink ejection port and are activated to pressurize the ink within the nozzle chamber thereby causing the ejection of ink through the ejection port.

Turning now to FIGS. 1, 2 and 3, there is illustrated the basic operational principles of the preferred embodiment. FIG. 1 illustrates a single nozzle arrangement 1 in its quiescent state. The arrangement 1 includes a nozzle chamber 2 which is normally filled with ink so as to form a meniscus 3 in an ink ejection port 4. The nozzle chamber 2 is formed within a wafer 5. The nozzle chamber 2 is supplied with ink via an ink supply channel 6 which is etched through the wafer 5 with a highly isotropic plasma etching system. A suitable etcher can be the Advance Silicon Etch (ASE) system available from Surface Technology Systems of the United Kingdom.

A top of the nozzle arrangement 1 includes a series of 45 radially positioned actuators 8, 9. These actuators comprise a polytetrafluoroethylene (PTFE) layer and an internal serpentine copper core 17. Upon heating of the copper core 17, the surrounding PTFE expands rapidly resulting in a generally downward movement of the actuators 8, 9. Hence, when it is desired to eject ink from the ink ejection port 4, a current is passed through the actuators 8, 9 which results in them bending generally downwards as illustrated in FIG. 2. The downward bending movement of the actuators 8, 9 results in a substantial increase in pressure within the nozzle chamber 2. The increase in pressure in the nozzle chamber 2 results in an expansion of the meniscus 3 as illustrated in FIG. 2.

The actuators 8, 9 are activated only briefly and subsequently deactivated. Consequently, the situation is as illustrated in FIG. 3 with the actuators 8, 9 returning to their original positions. This results in a general inflow of ink back into the nozzle chamber 2 and a necking and breaking of the meniscus 3 resulting in the ejection of a drop 12. The necking and breaking of the meniscus 3 is a consequence of the forward momentum of the ink associated with drop 12 and the backward pressure experienced as a result of the return of the actuators 8, 9 to their original positions. The

return of the actuators 8,9 also results in a general inflow of ink from the channel 6 as a result of surface tension effects and, eventually, the state returns to the quiescent position as illustrated in FIG. 1.

FIGS. 4(a) and 4(b) illustrate the principle of operation of the thermal actuator. The thermal actuator is preferably constructed from a material 14 having a high coefficient of thermal expansion. Embedded within the material 14 are a series of heater elements 15 which can be a series of conductive elements designed to carry a current. The conductive elements 15 are heated by passing a current through the elements 15 with the heating resulting in a general increase in temperature in the area around the heating elements 15. The position of the elements 15 is such that uneven heating of the material 14 occurs. The uneven increase in temperature causes a corresponding uneven expansion of the material 14. Hence, as illustrated in FIG. 4(b), the PTFE is bent generally in the direction shown.

In FIG. 5, there is illustrated a side perspective view of one embodiment of a nozzle arrangement constructed in accordance with the principles previously outlined. The nozzle chamber 2 is formed with an isotropic surface etch of the wafer 5. The wafer 5 can include a CMOS layer including all the required power and drive circuits. Further, the actuators 8, 9 each have a leaf or petal formation which extends towards a nozzle rim 28 defining the ejection port 4. The normally inner end of each leaf or petal formation is displaceable with respect to the nozzle rim 28. Each actuator 8, 9 has an internal copper core 17 defining the element 15. The core 17 winds in a serpentine manner to provide for substantially unhindered expansion of the actuators 8, 9. The operation of the actuators 8, 9 is as illustrated in FIG. 4(a) and FIG. 4(b) such that, upon activation, the actuators 8 bend as previously described resulting in a displacement of each petal formation away from the nozzle rim 28 and into the nozzle chamber 2. The ink supply channel 6 can be created via a deep silicon back edge of the wafer 5 utilizing a plasma etcher or the like. The copper or aluminum core 17 can provide a complete circuit. A central arm 18 which can include both metal and PTFE portions provides the main structural support for the actuators 8, 9.

Turning now to FIG. 6 to FIG. 13, one form of manufacture of the nozzle arrangement 1 in accordance with the principles of the preferred embodiment is shown. The nozzle arrangement 1 is preferably manufactured using micro-electromechanical (MEMS) techniques and can include the following construction techniques:

As shown initially in FIG. 6, the initial processing starting material is a standard semi-conductor wafer 20 having a complete CMOS level 21 to a first level of metal. The first level of metal includes portions 22 which are utilized for providing power to the thermal actuators 8, 9.

The first step, as illustrated in FIG. 7, is to etch a nozzle region down to the silicon wafer 20 utilizing an appropriate mask.

Next, as illustrated in FIG. 8, a 2 μm layer of polytetrafluoroethylene (PTFE) is deposited and etched so as to define vias 24 for interconnecting multiple levels.

Next, as illustrated in FIG. 9, the second level metal layer is deposited, masked and etched to define a heater structure 25. The heater structure 25 includes via 26 interconnected with a lower aluminum layer.

Next, as illustrated in FIG. 10, a further 2 μm layer of PTFE is deposited and etched to the depth of 1 μm utilizing a nozzle rim mask to define the nozzle rim 28 in addition to ink flow guide rails 29 which generally restrain any wicking along the surface of the PTFE layer. The guide rails 29

surround small thin slots and, as such, surface tension effects are a lot higher around these slots which in turn results in minimal outflow of ink during operation.

Next, as illustrated in FIG. 11, the PTFE is etched utilizing a nozzle and actuator mask to define a port portion 30 and slots 31 and 32.

Next, as illustrated in FIG. 12, the wafer is crystallographically etched on a <111> plane utilizing a standard crystallographic etchant such as KOH. The etching forms a chamber 33, directly below the port portion 30.

In FIG. 13, the ink supply channel 34 can be etched from the back of the wafer utilizing a highly anisotropic etcher such as the STS etcher from Silicon Technology Systems of United Kingdom. An array of ink jet nozzles can be formed simultaneously with a portion of an array 36 being illustrated in FIG. 14. A portion of the printhead is formed simultaneously and diced by the STS etching process. The array 36 shown provides for four column printing with each separate column attached to a different color ink supply channel being supplied from the back of the wafer. Bond pads 37 provide for electrical control of the ejection mechanism.

In this manner, large pagewidth printheads can be fabricated so as to provide for a drop-on-demand ink ejection mechanism.

One form of detailed manufacturing process which can be used to fabricate monolithic ink jet printheads operating in accordance with the principles taught by the present embodiment can proceed utilizing the following steps:

1. Using a double-sided polished wafer 60, complete a 0.5 micron, one poly, 2 metal CMOS process 61. This step is shown in FIG. 16. For clarity, these diagrams may not be to scale, and may not represent a cross section though any single plane of the nozzle. FIG. 15 is a key to representations of various materials in these manufacturing diagrams, and those of other cross-referenced ink jet configurations.

2. Etch the CMOS oxide layers down to silicon or second level metal using Mask 1. This mask defines the nozzle cavity and the edge of the chips. This step is shown in FIG. 16.

3. Deposit a thin layer (not shown) of a hydrophilic polymer, and treat the surface of this polymer for PTFE adherence.

4. Deposit 1.5 microns of polytetrafluoroethylene (PTFE) 62.

5. Etch the PTFE and CMOS oxide layers to second level metal using Mask 2. This mask defines the contact vias for the heater electrodes. This step is shown in FIG. 17.

6. Deposit and pattern 0.5 microns of gold 63 using a lift-off process using Mask 3. This mask defines the heater pattern. This step is shown in FIG. 18.

7. Deposit 1.5 microns of PTFE 64.

8. Etch 1 micron of PTFE using Mask 4. This mask defines the nozzle rim 65 and the rim at the edge 66 of the nozzle chamber. This step is shown in FIG. 19.

9. Etch both layers of PTFE and the thin hydrophilic layer down to silicon using Mask 5. This mask defines a gap 67 at inner edges of the actuators, and the edge of the chips. It also forms the mask for a subsequent crystallographic etch. This step is shown in FIG. 20.

10. Crystallographically etch the exposed silicon using KOH. This etch stops on <111> crystallographic planes 68, forming an inverted square pyramid with sidewall angles of 54.74 degrees. This step is shown in FIG. 21.

11. Back-etch through the silicon wafer (with, for example, an ASE Advanced Silicon Etcher from Surface Technology Systems) using Mask 6. This mask defines the

ink inlets 69 which are etched through the wafer. The wafer is also diced by this etch. This step is shown in FIG. 22.

12. Mount the printheads in their packaging, which may be a molded plastic former incorporating ink channels which supply the appropriate color ink to the ink inlets 69 at the back of the wafer.

13. Connect the printheads to their interconnect systems. For a low profile connection with minimum disruption of airflow, TAB may be used. Wire bonding may also be used if the printer is to be operated with sufficient clearance to the paper.

14. Fill the completed print heads with ink 70 and test them. A filled nozzle is shown in FIG. 23.

The presently disclosed ink jet printing technology is potentially suited to a wide range of printing systems including: color and monochrome office printers, short run digital printers, high speed digital printers, offset press supplemental printers, low cost scanning printers high speed pagewidth printers, notebook computers with inbuilt pagewidth printers, portable color and monochrome printers, color and monochrome copiers, color and monochrome facsimile machines, combined printer, facsimile and copying machines, label printers, large format plotters, photograph copiers, printers for digital photographic "minilabs", video printers, PHOTO CD (PHOTO CD is a registered trade mark of the Eastman Kodak Company) printers, portable printers for PDAs, wallpaper printers, indoor sign printers, billboard printers, fabric printers, camera printers and fault tolerant commercial printer arrays.

It would be appreciated by a person skilled in the art that numerous variations and/or modifications may be made to the present invention as shown in the specific embodiments without departing from the spirit or scope of the invention as broadly described. The present embodiments are, therefore, to be considered in all respects to be illustrative and not restrictive.

Ink Jet Technologies

The embodiments of the invention use an ink jet printer type device. Of course many different devices could be used. However, presently popular ink jet printing technologies are unlikely to be suitable.

The most significant problem with thermal ink jet is power consumption. This is approximately 100 times that required for high speed, and stems from the energy-inefficient means of drop ejection. This involves the rapid boiling of water to produce a vapor bubble which expels the ink. Water has a very high heat capacity, and must be superheated in thermal ink jet applications. This leads to an efficiency of around 0.02%, from electricity input to drop momentum (and increased surface area) out.

The most significant problem with piezoelectric ink jet is size and cost. Piezoelectric crystals have a very small deflection at reasonable drive voltages, and therefore require a large area for each nozzle. Also, each piezoelectric actuator must be connected to its drive circuit on a separate substrate. This is not a significant problem at the current limit of around 300 nozzles per printhead, but is a major impediment to the fabrication of pagewidth printheads with 19,200 nozzles.

Ideally, the ink jet technologies used meet the stringent requirements of in-camera digital color printing and other high quality, high speed, low cost printing applications. To meet the requirements of digital photography, new ink jet technologies have been created. The target features include:

low power (less than 10 Watts)

High-resolution capability (1,600 dpi or more)

photographic quality output
low manufacturing cost
small size (pagewidth times minimum cross section)
high speed (<2 seconds per page).

5 All of these features can be met or exceeded by the ink jet systems described below with differing levels of difficulty. Forty-five different ink jet technologies have been developed by the Assignee to give a wide range of choices for high volume manufacture. These technologies form part of separate applications assigned to the present Assignee as set out in the table below under the heading Cross References to Related Applications.

15 The ink jet designs shown here are suitable for a wide range of digital printing systems, from battery powered one-time use digital cameras, through to desktop and network printers, and through to commercial printing systems.

20 For ease of manufacture using standard process equipment, the printhead is designed to be a monolithic 0.5-micron CMOS chip with MEMS post processing. For color photographic applications, the printhead is 100 mm long, with a width which depends upon the ink jet type. The smallest printhead designed is IJ38, which is 0.35 mm wide, giving a chip area of 35 square mm. The printheads each contain 19,200 nozzles plus data and control circuitry.

25 Ink is supplied to the back of the printhead by injection molded plastic ink channels. The molding requires 50 micron features, which can be created using a lithographically micromachined insert in a standard injection molding tool. Ink flows through holes etched through the wafer to the nozzle chambers fabricated on the front surface of the wafer. The printhead is connected to the camera circuitry by tape automated bonding.

Tables of Drop-on-Demand Ink Jets

30 35 Eleven important characteristics of the fundamental operation of individual ink jet nozzles have been identified. These characteristics are largely orthogonal, and so can be elucidated as an eleven dimensional matrix. Most of the eleven axes of this matrix include entries developed by the present assignee.

The following tables form the axes of an eleven dimensional table of ink jet types.

40 45 50 55 60 65 70 75 80 85 90 95
Actuator mechanism (18 types)
Basic operation mode (7 types)
Auxiliary mechanism (8 types)
Actuator amplification or modification method (17 types)
Actuator motion (19 types)
Nozzle refill method (4 types)
Method of restricting back-flow through inlet (10 types)
Nozzle clearing method (9 types)
Nozzle plate construction (9 types)
Drop ejection direction (5 types)
Ink type (7 types)

The complete eleven dimensional table represented by these axes contains 36.9 billion possible configurations of ink jet nozzle. While not all of the possible combinations result in a viable ink jet technology, many million configurations are viable. It is clearly impractical to elucidate all of the possible configurations. Instead, certain ink jet types have been investigated in detail. These are designated IJ01 to IJ45 above which matches the docket numbers in the table under the heading Cross References to Related Applications.

65 Other ink jet configurations can readily be derived from these forty-five examples by substituting alternative configurations along one or more of the 11 axes. Most of the

IJ01 to IJ45 examples can be made into ink jet printheads with characteristics superior to any currently available ink jet technology.

Where there are prior art examples known to the inventor, one or more of these examples are listed in the examples column of the tables below. The IJ01 to IJ45 series are also listed in the examples column. In some cases, print technology may be listed more than once in a table, where it shares characteristics with more than one entry.

Suitable applications for the ink jet technologies include: Home printers, Office network printers, Short run digital printers, Commercial print systems, Fabric printers, Pocket printers, Internet WWW printers, Video printers, Medical imaging, Wide format printers, Notebook PC printers, Fax machines, Industrial printing systems, Photocopiers, Photographic minilabs etc.

The information associated with the aforementioned 11 dimensional matrix is set out in the following tables.

		Description	Advantages	Disadvantages	Examples
	5	Electro-strictive	An electric field is used to activate electrostriction in relaxor materials such as lead lanthanum zirconate titanate (PLZT) or lead magnesium niobate (PMN).	Low power consumption Many ink types can be used Low thermal expansion Electric field strength required (approx. 3.5 V/ μ m) can be generated without difficulty Does not require electrical poling	Low maximum strain (approx. 0.01%) Large area required for actuator due to low strain Response speed is marginal (~10 μ s) High voltage drive transistors required Full pagewidth print heads impractical due to actuator size
	10				Seiko Epson, Usui et al JP 253401/96 IJ04
	15				
	20	Ferro-electric	An electric field is used to induce a phase transition between the antiferroelectric (AFE) and ferroelectric (FE) phase. Perovskite materials such as tin modified lead lanthanum zirconate titanate (PLZSnT) exhibit large strains of up to 1% associated with the AFE to FE phase transition.	Low power consumption Many ink types can be used Fast operation (<1 μ s) Relatively high longitudinal strain High efficiency Electric field strength of around 3 V/ μ m can be readily provided	Difficult to integrate with electronics Unusual materials such as PLZSnT are required. Actuators require a large area
	25				IJ04
	30				
	35				
	40	Electro-static plates	Conductive plates are separated by a compressible or fluid dielectric (usually air). Upon application of a voltage, the plates attract each other and displace ink, causing drop ejection. The conductive plates may be in a comb or honeycomb structure, or stacked to increase the surface area and therefore the force.	Low power consumption Many ink types can be used Fast operation	Difficult to operate electrostatic devices in an aqueous environment. The electrostatic actuator will normally need to be separated from the ink. Very large area required to achieve high forces. High voltage drive transistors may be required. Full pagewidth print heads are not competitive due to actuator size
	45				IJ02, IJ04
	50				
	55				
	60	Electro-static pull on ink	A strong electric field is applied to the ink, whereupon electrostatic attraction accelerates the ink towards the print medium.	Low current consumption Low temperature	High voltage required May be damaged by sparks due to air breakdown Required field strength increases as the drop size

	Description	Advantages	Disadvantages	Examples		Description	Advantages	Disadvantages	Examples
Permanent magnet electro-magnetic	An electro-magnet directly attracts a permanent magnet, displacing ink and causing drop ejection. Rare earth magnets with a field strength around 1 Tesla can be used. Examples are: Samarium Cobalt (SaCo) and magnetic materials in the neodymium iron boron family (NdFeB, NdDyFeBNb, NdDyFeB, etc)	Low power consumption. Many ink types can be used. Fast operation. High efficiency. Easy extension from single nozzles to pagewidth print heads	Decreases High voltage drive transistors required. Electrostatic field attracts dust	Complex fabrication. Permanent magnetic material such as Neodymium Iron Boron (NdFeB) required. Copper metalization should be used for long electro-migration lifetime and low resistivity. Pigmented inks are usually infeasible	5	the print head, for example with rare earth permanent magnets.	extension from single nozzles to pagewidth print heads	required Copper metalization should be used for long electro-migration lifetime and low resistivity. Pigmented inks are usually infeasible	
Soft magnetic core electro-magnetic	A solenoid induced a magnetic field in a soft magnetic core or yoke fabricated from a ferrous material such as electroplated iron alloys such as CoNiFe [1], CoFe, or NiFe alloys. Typically, the soft magnetic material is in two parts, which are normally held apart by a spring. When the solenoid is actuated, the two parts attract, displacing the ink.	Low power consumption. Many ink types can be used. Fast operation. High efficiency. Easy extension from single nozzles to pagewidth print heads	Decreases High voltage drive transistors required. Electrostatic field attracts dust	Complex fabrication. Permanent magnetic material such as Neodymium Iron Boron (NdFeB) required. Copper metalization should be used for long electro-migration lifetime and low resistivity. Pigmented inks are usually infeasible	10	Only the current carrying wire need be fabricated on the print head, simplifying materials requirements.	Many ink types can be used. Fast extension from single nozzles to pagewidth print heads	Force acts as a twisting motion	Fischbeck, U.S. Pat No. 4,032,929
Lorenz force	The Lorenz force acting on a current carrying wire in a magnetic field is utilized. This allows the magnetic field to be supplied externally to	Low power consumption. Many ink types can be used. Fast operation. High efficiency. Easy	Decreases High voltage drive transistors required. Electrostatic field attracts dust	Complex fabrication. Permanent magnetic material such as Neodymium Iron Boron (NdFeB) required. Copper metalization should be used for long electro-migration lifetime and low resistivity. Pigmented inks are usually infeasible	15	Magneto-striction	The actuator uses the giant magneto-strictive effect of materials such as Terfenol-D (an alloy of terbium, dysprosium and iron developed at the Naval Ordnance Laboratory, hence Ter-Fe-NOL).	Many ink types can be used. Fast extension from single nozzles to pagewidth print heads	Force acts as a twisting motion
					20	For best efficiency, the actuator should be pre-stressed to approx. 8 MPa.	High force is available	Unusual materials such as Terfenol-D are required. High local currents required. Copper metalization should be used for long electro-migration lifetime and low resistivity. Pre-stressing may be required	U.S. Pat No. 4,032,929
					25	Surface tension reduction	Ink under positive pressure is held in a nozzle by surface tension.	Low power consumption. Simple construction. No unusual materials required in fabrication	Silverbrook, EP 0771 658
					30	The surface tension of the ink is reduced below the bubble threshold, causing the ink to egress from the nozzle.	High efficiency. Easy extension from single nozzles to pagewidth print heads	Requires supplementary force to effect drop separation. Requires special ink surfactants. Speed may be limited by surfactant properties	A2 and related patent applications
					35	Viscosity reduction	The ink viscosity is locally reduced to select which drops are to be ejected. A viscosity reduction can be achieved electro-thermally with most inks, but special inks can be engineered for a 100:1 viscosity reduction.	Simple construction. No unusual materials required in fabrication. Easy extension from single nozzles to pagewidth print heads	Silverbrook, EP 0771 658
					40			Requires supplementary force to effect drop separation. Requires special ink viscosity properties. High speed is difficult to achieve. Requires oscillating ink pressure. A high temperature difference (typically 80 degrees) is required	A2 and related patent applications

Description	Advantages	Disadvantages	Examples
Oscillating ink pressure (including acoustic stimulation)	The ink pressure oscillates, providing much energy. The actuator selects which drops are to be fired by selectively blocking or enabling nozzles. The ink pressure oscillation may be achieved by vibrating the print head, or preferably by an actuator in the ink supply.	Oscillating ink pressure can provide a refill pulse, allowing higher operating speed with much lower energy. Acoustic lenses can be used to focus the sound on the nozzles	Requires external ink oscillator. Ink pressure phase and amplitude must be carefully controlled. Acoustic reflections in the ink chamber must be designed for
Media proximity	The print head is placed in close proximity to the print medium. Selected drops protrude from the print head further than unselected drops, and contact the print medium. The drop soaks into the medium fast enough to cause drop separation.	Low power accuracy. Simple print head construction	Precision assembly required. Paper fibers may cause problems. Cannot print on rough substrates
Transfer roller	Drops are printed to a transfer roller instead of straight to the print medium. A transfer roller can also be used for proximity drop separation.	High accuracy. Wide range of print construction	Bulky. Expensive. Complex construction
Electro-static	An electric field is used to accelerate selected drops towards the print medium.	Low power. Simple print head construction	Field strength required for separation of small drops is near or above air breakdown
Direct magnetic	A magnetic field is used to	Low power. Simple	Requires magnetic ink

Actuator stack	A series of thin actuators are stacked. This can be appropriate where actuators require high electric field strength, such as electrostatic and piezo-electric actuators.	Increased travel Reduced drive voltage	Increased fabrication complexity Increased possibility of short circuits due to pinholes	Some piezoelectric ink jets IJ04	10 15 20 25
Multiple actuators	Multiple smaller actuators are used simultaneously to move the ink. Each actuator need provide only a portion of the force required.	Increases the force available from an actuator to move the ink. Each actuator can be positioned to control ink flow accurately	Actuator forces may not add linearly, reducing efficiency	IJ12, IJ13, IJ18, IJ20, IJ22, IJ28, IJ42, IJ43	35
Linear Spring	A linear spring is used to transform a motion with small travel and high force into a longer travel, lower force motion.	Matches low travel requirements Non-contact method of motion transformation	Requires print head area for the spring	IJ15	40 45
Coiled actuator	A bend actuator is coiled to provide greater travel in a reduced chip area.	Increases travel Reduces chip area Planar implementations are relatively easy to fabricate.	Generally restricted to planar implementations due to extreme fabrication difficulty in other orientations.	IJ17, IJ21, IJ34, IJ35	50 55
Flexure bend actuator	A bend actuator has a small region near the fixture point, which flexes much more readily than the remainder of the actuator.	Simple means of increasing travel of a bend actuator	Care must be taken not to exceed the elastic limit in the flexure area Stress distribution is very uneven Difficult to accurately	IJ10, IJ19, IJ33	60 65

-continued

	Description	Advantages	Disadvantages	Examples
	The actuator flexing is effectively converted from an even coiling to an angular bend, resulting in greater travel of the actuator tip.	Very low energy enables or disables movement of an ink pusher that is controlled in a bulk manner.	Complex construction Requires external force Unsuitable for pigmented inks	IJ10
	Catch	The actuator controls a small catch. The catch either enables or disables movement of an ink pusher that is controlled in a bulk manner.	Very low actuator energy	IJ13
	Gears	Gears can be used to increase travel at the expense of duration. Circular gears, rack and pinion, ratchets, and other gearing methods can be used.	Low force, low travel actuators can be used	Several actuator cycles are required
	Buckle plate	A buckle plate can be used to change a slow actuator into a fast motion. It can also convert a high force, low travel actuator into a high travel, medium force motion.	Very fast movement achievable	Moving parts are required
	Lever	A lever and fulcrum is used to transform a motion with small travel and high force into a motion with longer travel and lower force. The lever can also reverse the direction of travel.	High stress around the fulcrum	S. Hirata et al, "An Ink-jet Head Using Diaphragm Micro-actuator", Proc. IEEE MEMS, Feb. 1996, pp 418-423. IJ18, IJ27
	Tapered magnetic pole	A tapered magnetic pole can increase travel at the expense of force.	Linearizes the magnetic force/distance curve	IJ14
				IJ32, IJ36, IJ37
				IJ28
	Rotary impeller	The actuator is connected to a rotary impeller. A small angular deflection of the actuator results in a rotation of the impeller vanes, which creates a flow of air through the nozzle.	High mechanical advantage	Complex construction
			The ratio of force to travel of the actuator can be matched to the nozzle requirements	Unsuitable for pigmented inks

	Description	Advantages	Disadvantages	Examples
Acoustic lens	which push the ink against stationary vanes and out of the nozzle. A refractive or diffractive (e.g. zone plate) acoustic lens is used to concentrate sound waves.	by varying the number of impeller vanes	Large area required Only relevant for acoustic ink jets	1993 Hadimioglu et al, EUP 550,192 1993 Elrod et al, EUP 572,220
Sharp conductive point	A sharp point is used to concentrate an electrostatic field.	Simple construction	Difficult to fabricate using standard VLSI processes for a surface ejecting inkjet Only relevant for electrostatic ink jets	Tone-jet
ACTUATOR MOTION				

	Description	Advantages	Disadvantages	Examples
Volume expansion	The volume of the actuator changes, pushing the ink in all directions.	Simple construction in the case of thermal ink jet	High energy is typically required to achieve volume expansion. This leads to thermal stress, cavitation, and clogging in thermal ink jet implementations	Hewlett-Packard Thermal Ink jet Canon Bubblejet
Linear, normal to chip surface	The actuator moves in a direction normal to the print head surface. The nozzle is typically in the line of movement.	Efficient coupling to ink drops ejected normal to the surface	High fabrication complexity may be required to achieve perpendicular motion	IJ01, IJ02, IJ04, IJ07, IJ11, IJ14
Parallel to chip surface	The actuator moves parallel to the print head surface. Drop ejection may still be normal to the surface.	Suitable for planar fabrication	Fabrication complexity Friction Stiction	IJ12, IJ13, IJ15, IJ33, IJ34, IJ35, IJ36
Membrane push	An actuator with a high force but small area is used to push a stiff membrane that is in contact with the ink.	The effective area of the actuator becomes the membrane area	Fabrication complexity Actuator size Difficulty of integration in a VLSI process	1982 Howkins U.S. Pat No. 4,459,601
Rotary	The actuator causes the rotation of some element, such as a grill or impeller	Rotary levers may be used to increase travel Small chip area requirements	Device complexity May have friction at a pivot point	IJ05, IJ08, IJ13, IJ28
Bend	The actuator bends when energized. This may be due to differential thermal expansion, piezoelectric expansion,	A very small change in dimensions can be converted to a large motion.	Requires the actuator to be made from at least two distinct layers, or to have a thermal difference across the	1970 Kyser et al U.S. Pat No. 3,946,398 1973 Stemme U.S. Pat No. 3,747,120 IJ03, IJ09,
-continued				
5				
10	Swivel		magneto-striction, or other form of relative dimensional change.	actuator IJ10, IJ19, IJ23, IJ24, IJ25, IJ29, IJ30, IJ31, IJ33, IJ34, IJ35 IJ06
15			The actuator swivels around a central pivot, This motion is suitable where there are opposite forces applied to opposite sides of the paddle, e.g. Lorenz force.	Allows operation where the net linear force on the paddle is zero Small chip area requirements
20	Straighten		The actuator is normally bent, and straightens when energized.	Can be used with shape memory alloys where the austenitic phase is planar Requires careful balance of stresses to ensure that the quiescent bend is accurate IJ26, IJ32
25	Double bend		The actuator bends in one direction when one element is energized, and bends the other way when another element is energized.	One actuator can be used to power two nozzles. Reduced chip size. Not sensitive to ambient temperature
30			Energizing the actuator causes a shear motion in the actuator material.	Can increase the effective travel of piezoelectric actuators
35	Shear		The actuator squeezes an ink reservoir, forcing ink from a constricted nozzle.	Not readily applicable to other actuator mechanisms
40	Radial constriction		Relatively easy to fabricate single nozzles from glass tubing as macroscopic structures	1985 Fishbeck U.S. Pat No. 4,584,590
45			A coiled actuator uncoils or coils more tightly. The motion of the free end of the actuator ejects the ink.	High force required Inefficient Difficult to integrate with VLSI processes
50	Coil/ uncoil		Easy to fabricate as a planar VLSI process	1970 Zoltan U.S. Pat No. 3,683,212
			Small area required, therefore low cost	Poor out-of-plane stiffness
55	Bow		The actuator bows (or buckles) in the middle when energized.	Difficult to fabricate for non-planar devices
				IJ17, IJ21, IJ34, IJ35
				IJ16, IJ18, IJ27
				IJ18
60	Push-Pull		Two actuators control a shutter. One actuator pulls the shutter, and the other pushes it.	Can increase the speed of travel Mechanically rigid
65	Curl inwards		A set of actuators curl inwards to reduce the	Maximum travel is constrained High force required
				The structure is pinned at both ends, so has a high out-of-plane rigidity
				Not readily suitable for ink jets which directly push the ink
				IJ20, IJ42
				Good fluid flow to the region behind the

	Description	Advantages	Disadvantages	Examples
Curl outwards	volume of ink that they enclose. A set of actuators curl outwards, pressurizing ink in a chamber surrounding the actuators, and expelling ink from a nozzle in the chamber.	actuator increases efficiency Relatively simple construction	Relatively large chip area	IJ43
Iris	Multiple vanes enclose a volume of ink. These simultaneously rotate, reducing the volume between the vanes.	High efficiency Small chip area	High fabrication complexity Not suitable for pigmented inks	IJ22
Acoustic vibration	The actuator vibrates at a high frequency.	The actuator can be physically distant from the ink	Large area required for efficient operation at useful frequencies Acoustic coupling and crosstalk Complex drive circuitry	1993 Hadimioglu et al, EUP 550,192 1993 Elrod et al, EUP 572,220
None	In various ink jet designs the actuator does not move.	No moving parts	Poor control of drop volume and position Various other tradeoffs are required to eliminate moving parts	Silverbrook, EP 0771 658 A2 and related patent applications Tone-jet

NOZZLE REFILL METHOD

	Description	Advantages	Disadvantages	Examples
Surface tension	This is the normal way that ink jets are refilled. After the actuator is energized, it typically returns rapidly to its normal position. This rapid return sucks in air through the nozzle opening. The ink surface tension at the nozzle then exerts a small force restoring the meniscus to a minimum area. This force refills the nozzle.	Fabrication simplicity Operational simplicity	Low speed Surface tension force relatively small compared to actuator force Long refill time usually dominates the total repetition rate	Thermal ink jet Piezoelectric inkjet IJ01-IJ07, IJ10-IJ14, IJ16, IJ20, IJ22-IJ45
Shuttered oscillating ink pressure	Ink to the nozzle chamber is provided at a pressure that oscillates at twice the drop ejection	High speed Low actuator energy, as a pressure that need only open or close the shutter,	Requires common ink pressure oscillator	IJ08, IJ13, IJ15, IJ17, IJ18, IJ19, IJ21

-continued

	Description	Advantages	Disadvantages	Examples
	frequency.	instead of ejecting the ink drop		
5	When a drop is to be ejected, the shutter is opened for 3 half cycles: drop ejection, actuator return, and refill. The shutter is then closed to prevent the nozzle chamber emptying during the next negative pressure cycle.			
10				
15				
20	Refill actuator	After the main actuator has ejected a drop a second (refill) actuator is energized. The refill actuator pushes ink into the nozzle chamber. The refill actuator returns slowly, to prevent its return from emptying the chamber again.	High speed, as the nozzle is actively refilled	Requires two independent actuators per nozzle IJ09
25				
30				
35	Positive ink pressure	The ink is held at a slight positive pressure. After the ink drop is ejected, the nozzle chamber fills quickly as possible	High refill rate, high drop repetition rate is possible	Surface spill must be prevented Highly hydrophobic print head surfaces are required Silverbrook, EP 0771 658 A2 and related patent applications Alternative for: IJ01-IJ07, IJ10-IJ14, IJ16, IJ20, IJ22-IJ45
40				
	METHOD OF RESTRICTING BACK-FLOW THROUGH INLET			
45	Long inlet channel	The ink inlet channel to the nozzle chamber is made long and relatively narrow, relying on viscous drag to reduce inlet back-flow.	Design simplicity Operational simplicity Reduces crosstalk	Restricts refill rate May result in a relatively large chip area Only partially effective Thermal ink jet Piezoelectric inkjet IJ42, IJ43
50	Positive ink pressure	The ink is under a selection and positive separation forces that in the quiescent state can be reduced some of the ink drop already protrudes from the nozzle. This reduces the pressure in the nozzle	Drop selection and separation forces can be reduced Fast refill time	Requires a method (such as a nozzle rim or effective hydrophobizing, or both) to prevent flooding of the ejection surface of the print head. Silverbrook, EP 0771 658 A2 and related patent applications Possible operation of the following: IJ01-IJ07, IJ09-IJ12, IJ14, IJ16, IJ20, IJ22, IJ23-IJ34, IJ36-IJ41, IJ44
55				
60				
65				

-continued

	Description	Advantages	Disadvantages	Examples	
Baffle	in a reduction in ink pushed out through the inlet. One or more baffles are placed in the inlet ink flow. When the actuator is energized, the rapid ink movement creates eddies which restrict the flow through the inlet. The slower refill process is unrestricted, and does not result in eddies.	The refill rate is not as restricted as the long inlet method. Reduces crosstalk	Design complexity May increase fabrication complexity (e.g. Tektronix hot melt Piezoelectric print heads).	TIP Thermal Ink Jet Tektronix piezoelectric ink jet	5
Flexible flap restricts inlet	In this method recently disclosed by Canon, the expanding actuator (bubble) pushes ink jet devices on a flexible flap that restricts the inlet.	Significantly reduces back-flow for edge-shooter thermal ink jet devices	Not applicable to most ink jet configurations Increased fabrication complexity Inelastic deformation of polymer flap results in creep over extended use	Canon	10
Inlet filter	A filter is located between the ink inlet and the nozzle chamber. The filter has a multitude of small holes or slots, restricting ink flow. The filter also removes particles which may block the nozzle.	Additional advantage of ink filtration Ink filter may be fabricated with no additional process steps	Restricts refill rate May result in complex construction	IJ04, IJ12, IJ24, IJ27, IJ29, IJ30	15
Small inlet compared to nozzle	The ink inlet channel to the nozzle chamber has a substantially smaller cross section than that of the nozzle, resulting in easier ink egress out of the nozzle than out of the inlet.	Design simplicity	Restricts refill rate May result in a relatively large chip area Only partially effective	IJ02, IJ37, IJ44	20
Inlet shutter	A secondary actuator controls the position of a shutter, closing off the ink inlet when the main actuator is energized.	Increases speed of the ink-jet print head operation	Requires separate refill actuator and drive circuit	IJ09	25
The inlet is located	The method avoids the	Back-flow problem is	Requires careful design	IJ01, IJ03, IJ05, IJ06,	30

-continued

	Description	Advantages	Disadvantages	Examples
	problem of inlet back-flow by arranging the ink-pushing surface of the actuator between the inlet and the nozzle.	eliminated	to minimize the negative pressure behind the paddle	IJ07, IJ10, IJ11, IJ14, IJ16, IJ22, IJ23, IJ25, IJ28, IJ31, IJ32, IJ33, IJ34, IJ35, IJ36, IJ39, IJ40, IJ41
	Part of the actuator moves to shut off the inlet	The actuator and a wall of the ink chamber are arranged so that the motion of the actuator closes off the inlet.	Significant reductions in back-flow can be achieved Compact designs possible	Small increase in fabrication complexity
	Nozzle actuator does not result in ink back-flow	In some configurations of ink jet, there is no expansion or movement of an actuator which may cause ink back-flow through the inlet.	Ink back-flow problem is eliminated	None related to ink back-flow on actuation
	Normal nozzle firing	All of the nozzles are fired periodically, before the ink has a chance to dry. When not in use the nozzles are sealed (capped) against air. The nozzle firing is usually performed during a special clearing cycle, after first moving the print head to a cleaning station.	No added complexity on the print head	None related to ink back-flow on actuation
	Extra power to ink heater	In systems which heat the ink, but do not boil it under normal situations, nozzle clearing can be achieved by overpowering the heater and boiling ink at the nozzle.	Can be highly effective if the heater is adjacent to the nozzle	None related to ink back-flow on actuation
	Rapid succession of actuator pulses	The actuator is fired in rapid succession. In some configurations, this may cause heat build-up at the nozzle which boils the ink, clearing and initiated	Does not require extra drive circuits on the print head	None related to ink back-flow on actuation
			Effectiveness depends substantially upon the configuration of the ink jet nozzle	None related to ink back-flow on actuation

NOZZLE CLEARING METHOD

-continued

Description	Advantages	Disadvantages	Examples
In other situations, it may cause sufficient vibrations to dislodge clogged nozzles.	by digital logic		IJ28, IJ29, IJ30, IJ31, IJ32, IJ33, IJ34, IJ36, IJ37, IJ38, IJ39, IJ40, IJ41, IJ42, IJ43, IJ44, IJ45
Extra power to ink pushing actuator	Where an actuator is not normally driven to the limit of its motion, nozzle clearing may be assisted by providing an enhanced drive signal to the actuator.	A simple solution where applicable	Not suitable where there is a hard limit to actuator movement
Acoustic resonance	An ultrasonic wave is applied to the ink chamber. This wave is of an appropriate amplitude and frequency to cause sufficient force at the nozzle to clear blockages. This is easiest to achieve if the ultrasonic wave acoustic actuators	A high nozzle clearing capability can be achieved May be implemented at very low cost in systems which include acoustic actuators	High implementation cost if system does not already include an acoustic actuator
Nozzle clearing plate	A micro-fabricated plate is pushed against the nozzles. The plate has a post for every nozzle. A post moves through each nozzle, displacing dried ink.	Can clear severely clogged nozzles	Accurate mechanical alignment is required Moving parts are required There is risk of damage to the nozzles Accurate fabrication is required
Ink pressure pulse	The pressure of the ink is increased so that ink streams from all of the nozzles. This may be used in conjunction with actuator energizing.	May be effective where other methods cannot be used	Silverbrook, EP 0771 658 A2 and related patent applications
Print head wiper	A flexible 'blade' is wiped across the print head surface. The blade is usually fabricated from a flexible polymer, e.g. rubber or synthetic elastomer.	Effective for planar print head surfaces Low cost	Difficult to use if print head surface is non-planar or very fragile Requires mechanical parts Blade can wear out in high volume print systems
Separate ink boiling	A separate heater is provided at the	Can be effective where other	Fabrication complexity

-continued

Description	Advantages	Disadvantages	Examples
5 heater	nozzle although the normal drop ejection mechanism does not require it. The heaters do not require individual drive circuits, as many nozzles can be cleared simultaneously, and no imaging is required.	nozzle clearing methods cannot be used Can be implemented at no additional cost in some ink jet configurations	jets
10			
15			
20	Electro-formed nickel	A nozzle plate is separately fabricated from electroformed nickel, and bonded to the print head chip.	Hewlett Packard Thermal Ink jet
25			
30	Laser ablated or drilled polymer	Individual nozzle holes are ablated by an intense UV laser in a nozzle plate, which is typically a polymer such as polyimide or polysulphone	NOZZLE PLATE CONSTRUCTION
35			
40	Silicon micro-machined	A separate nozzle plate is micromachined from single crystal silicon, and bonded to the print head wafer.	Each hole must be individually formed
45			Canon Bubblejet 1988 Sercel et al., SPIE, Vol. 998 Excimer Beam Applications, pp. 76-83
50	Glass capillaries	Fine glass capillaries are drawn from glass tubing. This method has been used for making individual nozzles, but is difficult to use for bulk manufacturing of print heads with thousands of nozzles.	Watanabe et al., U.S. Pat No. 5,208,604
55			Two part construction
60			High cost
65	Mono-lithic, surface micro-machined	The nozzle plate is deposited as a layer using standard VLSI	Requires sacrificial layer under the nozzle plate to form the nozzle
			A2 and related patent

	Description	Advantages	Disadvantages	Examples
using VLSI litho-graphic processes	deposition techniques. Nozzles are etched in the nozzle plate using VLSI lithography and etching.	Existing processes can be used	chamber Surface may be fragile to the touch	applications IJ01, IJ02, IJ04, IJ11, IJ12, IJ17, IJ18, IJ20, IJ22, IJ24, IJ27, IJ28, IJ29, IJ30, IJ31, IJ32, IJ33, IJ34, IJ36, IJ37, IJ38, IJ39, IJ40, IJ41, IJ42, IJ43, IJ44
Mono-lithic, etched through substrate	The nozzle plate is a buried etch stop in the wafer. Nozzle chambers are etched in the front of the wafer, and the wafer is thinned from the backside. Nozzles are then etched in the etch stop layer.	High accuracy ($<1 \mu\text{m}$) Monolithic Low cost No differential expansion	Requires long etch times Requires a support wafer	IJ03, IJ05, IJ06, IJ07, IJ08, IJ09, IJ10, IJ13, IJ14, IJ15, IJ16, IJ19, IJ21, IJ23, IJ25, IJ26
No nozzle plate	Various methods have been tried to eliminate the nozzles entirely, to prevent nozzle clogging. These include thermal bubble mechanisms and acoustic lens mechanisms	No nozzles to become clogged	Difficult to control drop position accurately Crosstalk problems	Ricoh 1995 Sekiya et al USP 5,412,413 1993 Hadimioglu et al EUP 550,192 1993 Elrod et al EUP 572,220
Trough	Each drop ejector has a trough through which a paddle moves. There is no nozzle plate.	Reduced manufacturing complexity Monolithic	Drop firing direction is sensitive to wicking.	IJ35
Nozzle slit instead of individual nozzles	The elimination of nozzle holes and replacement by a slit encompassing many actuator positions reduces nozzle clogging, but increases crosstalk due to ink surface waves	No nozzles to become clogged	Difficult to control drop position accurately Crosstalk problems	1989 Saito et al U.S. Pat No. 4,799,068

DROP EJECTION DIRECTION

Edge ('edge shooter')	Ink flow is along the surface of the chip, and ink drops are ejected from the chip edge.	Simple construction No silicon etching required Good heat sinking via substrate Mechanically strong	Nozzles limited to edge High resolution Fast color printing requires one print head per color	Canon Bubblejet 1979 Endo et al GB patent 2,007,162 Xerox heater-in-pit 1990 Hawkins

	Description	Advantages	Disadvantages	Examples	
Methyl Ethyl Ketone (MEK)	MEK is a highly volatile solvent used for industrial printing on difficult surfaces such as metals and plastics as aluminum cans.	Very fast drying Prints on various substrates such as metals and plastics	Odorous Flammable	(with significant restrictions) All IJ series ink jets	5
Alcohol (ethanol, 2-butanol, and others)	Alcohol based inks can be used where the printer must operate at temperatures below the freezing point of water. An example of this is in-camera consumer photographic printing.	Fast drying Operates at subfreezing temperatures Reduced paper cockle Low cost	Slight odor Flammable	All IJ series ink jets	10 15
Phase change (hot melt)	The ink is solid at room temperature, and is melted in the print head before jetting. Hot melt inks are usually wax based, with a melting point around 80° C. After jetting the ink freezes almost instantly upon contacting the print medium or a transfer roller.	No drying time - ink instantly freezes on the print medium Almost any print medium can be used No paper cockle occurs No wicking occurs No bleed occurs No strike-through occurs	High viscosity Printed ink typically has a 'waxy' feel Printed pages may 'block'	Tektronix hot melt piezoelectric ink jets 1989 Nowak U.S. Pat No. 4,820,346 All IJ series ink jets	25 30
Oil	Oil based inks are extensively used in offset printing. They have advantages in improved characteristics on paper (especially no wicking or cockle). Oil soluble dies and pigments are required.	High solubility medium for some dyes Does not cockle paper Does not wick through paper	High viscosity: this is a significant limitation for use in ink jets, which usually require a low viscosity. Some short chain and multi-branched oils have a sufficiently low viscosity. Slow drying	All IJ series ink jets	35 40 45 50

	Description	Advantages	Disadvantages	Examples
5	Micro-emulsion	A micro-emulsion is a stable, self forming emulsion of oil, water, and surfactant. The characteristic drop size is less than 100 nm, and is determined by the preferred curvature of the surfactant.	Stops ink bleed High dye solubility amphiphilic soluble dies can be used Can stabilize pigment suspensions	Viscosity higher than water All IJ series ink jets

We claim:

- 20 1. A fluid ejection chip that comprises:
a substrate; and
a plurality of nozzle arrangements positioned on the substrate, each nozzle arrangement comprising:
a nozzle chamber defining structure which defines a nozzle chamber and which includes a wall in which a fluid ejection port is defined; and
a series of thermal bend actuators arranged to extend from the nozzle chamber to the fluid ejection port so as to define said wall between the nozzle chamber and fluid ejection port; wherein,
the thermal bend actuators are configured to be activated on receipt of an electrical signal so as to all be displaced toward the substrate in order to reduce the volume of the nozzle chamber and be deactivated upon removal of the electrical signal so as to all be displaced back to their original positions in order to restore the volume of the nozzle chamber, thereby causing ejection of fluid through the fluid ejection port.
2. The fluid ejection chip of claim 1, in which each thermal bend actuator includes an actuating portion and a paddle positioned on the actuating portion, the actuating portion being anchored to the substrate and being displaceable on receipt of an electrical signal to displace the paddle, in turn, the paddles and the wall being substantially coplanar and the actuating portions being configured so that, upon receipt of said electrical signal, the actuating portions displace the paddles into the nozzle chamber to reduce a volume of the nozzle chamber, thereby ejecting fluid from the fluid ejection port.
3. The fluid ejection chip of claim 2 in which a periphery of each paddle is shaped to define a fluidic seal when the nozzle chamber is filled with fluid.
